(57) CLAIM

The ornamental design for a worm-shaped vitamin product, as shown and described.

DESCRIPTION

FIG. 1 is a side view of the worm-shaped vitamin product embodying the present invention.

FIG. 2 is a top view.

FIG. 3 is a front view.

FIG. 4 is a rear view; and,

FIG. 5 is a bottom view.

The worm-shaped vitamin product is symmetrical so that it has the same appearance from both sides.
